UNITED STATES PATENT OFFICE.

LOUIS MARIE GABRIEL DELAUNAY-BELLEVILLE, OF NEUILLY SUR SEINE, FRANCE, ASSIGNOR TO SOCIÉTÉ ANONYME DES ÉTABLISSEMENTS DE LAUNAY-BELLEVILLE, OF SEINE, FRANCE.

LOCKING DEVICE.

No. 842,632.

Specification of Letters Patent.

Patented Jan. 29, 1907.

Application filed April 12, 1906. Serial No. 311,371.

To all whom it may concern:

Be it known that I, LOUIS MARIE GABRIEL DELAUNAY-BELLEVILLE, a citizen of the French Republic, residing at Neuilly sur Seine, Department of Seine, France, have invented certain new and useful Improvements 5 in Locking Devices, of which the following is a specification.

This invention relates to locking devices, 10 and has for its object to provide a device of such class in a manner as hereinafter set forth for locking or clutching an operating element to an element to be operated and comprises a rocking lever carrying on one extremity a bolt for locking a shiftable element to a driving element and having its other extremity engaged by a guide for moving the bolt end of a lever to and from operative position, the arrangement permitting of rendering 15 the two elements solid or independent, starting from a given point in the longitudinal travel of the operating element.

The device is particularly adapted for use in connection with internal mechanism of 20 change-speed gears for motor-vehicles; but it may also be used for any purposes wherein it is found applicable.

In describing the invention in detail reference is had to the accompanying drawings, 25 which form a part of this specification, and wherein like reference characters denote corresponding parts throughout the several views, and in which—

Figure 1 is a longitudinal section through 30 a change-speed gear provided with the clutching device which forms the object of the invention. Fig. 2 is a cross-section through the same. Fig. 3 is a horizontal section through this change-speed gear. Fig. 4 35 shows the sliding gears and their operating mechanism. Figs. 5 and 6 represent, in side elevation and front elevation, the bolt-lever; and Fig. 7 is a plan view of the grooved guide serving to operate the bolt-lever.

This change-speed gear comprises a motor-shaft A, upon which is mounted a pinion 1 and the sliding gears 2 3. The pinion 1 and the gears 2 3 are solid with the shaft A in its rotation, but are capable of longitudinal displacement upon it. The shaft B to be driven is mounted in line with the motor-shaft A. It carries at its extremity adjacent

to the motor-shaft a pinion 4, having laterally-extending clutch-teeth 4². The gears 2 3 are provided on the side directed toward 55 the driven shaft with laterally-extending clutch-teeth 3², capable of being brought into engagement with the clutch-teeth 4² of the pinion 4, carried by the driven shaft.

Parallel with the shafts A and B there is 60 arranged an intermediate shaft C, to which are fixed gears of different diameters 1' 2' 3' 4'. A small shaft D, parallel with the other three shafts, carries a sleeve upon which two pinions 1² 1³ of the reversing-gear are fixed. 65 The gears 4 and 4' are always in mesh.

For the top speed with direct drive the clutch-teeth 3² and 4² are brought into mesh. For the third speed the sliding train is displaced in such a manner as to bring the gears 70 3 and 3' into mesh. For the second speed the gears 2 and 2' are brought into mesh. For the first speed the pinion 1 and gear 1' are caused to mesh. For the reverse the pinion 1 and gear 1' are caused to mesh with the pinions 1² and 1³, respectively.

The pinion 1 and the gears 2 3 are displaced for producing the different speeds by means of an operating-rod E. The operating-fork F of the pinion 1 is bolted to the rod 80 E. The fork G, controlling the displacements of the gears 2 3, on the other hand, is capable of sliding on the rod E and is not capable of displacing the gears 2 3, except when the locking device connects this fork 85 with the rod E.

The locking means comprises a lever H, capable of rocking around a shaft 5, carried by one arm of the fork G. The upper extremity of this lever forms a bolt 6. The lower extremity 7 of the lever is guided in the groove of a guide K, fixed to the gear-case. The bolt 6 is able to engage in a notch in the fork G and in a recess 6' in the rod E. When the bolt is engaged, the fork G is rendered 90 solid with the rod E, and the displacement of the rod E insures that of the gears 2 3. When, on the other hand, the bolt is not engaged, it is no longer in the recess 6' of the rod E and the gears 2 3 are no longer displaced. 95 The groove in the guide controls the heel 7 of the lever H, causing it to oscillate or rock around the shaft 5 in order to produce at the proper moment the engagement or disen-

gagement of the head 6, which forms the bolt. It limits the travel of the fork G in both directions.

So long as the heel 7 of the lever H is sliding in the rectilinear portion of the guide K, the bolt 6 is engaged. When, however, the rod E is pressed toward the left hand by a sufficient amount, the heel 7 of the lever H enters the curved part 7' of the groove, the lever rocks around the shaft 5, the bolt 6 is released, and at the same time the heel 7 of the lever strikes against the extremity of the groove and stops the displacement of the fork G, and consequently that of the gears 2 15 3 also.

In Figs. 1, 2, and 3 the bolt 6 of the lever H is engaged, the gears 2 3 occupy the end of their travel toward the right hand, and the clutch-teeth 3² and 4² are in mesh for the top 20 speed on the direct drive.

In Fig. 4 the bolt 6 of the lever H is released, the rod E has been displaced toward the left hand, the heel 7 of the lever has entered the curved part 7' of the guide-groove, 25 the bolt has been released, and the rod E, having continued its movement, has displaced only the pinion 1 toward the left hand. When the rod E is again moved toward the right hand, the cheek of the fork F 30 counters the gear 2. At this moment the recess 6' of the rod E comes just in front of the notch in the fork G, the fork F will push the gears 3 2, the fork G, and the lever H toward the right hand. The heel 7 of the lever H 35 will be gradually brought into the rectilinear

portion of the groove of the guide K and the bolt 6 of the lever H will enter the recess 6' of the rod E, in which it will be completely embedded as soon as the heel 7 of the bolt is situated in the rectilinear part of the groove 40 in the cam. The fork G, moving the sliding train, is at this moment solid with the operating-rod E. With this arrangement of bolt-lever and guide-cam the engagement and release take place automatically always at the 45 same point in the travel of the rod E, and it is impossible for the mechanism to get out of order.

Having now particularly described and ascertained the nature of my invention and in 50 what manner the same is to be performed, I declare that what I claim is—

In combination, a driving element, a shiftable and rotatable element carried thereby, a rod, a fork shiftable upon said rod and adapted to engage the rotatable element, a shaft 55 carried by the fork, a lever rocking upon said shaft and having a head constituting a bolt adapted to engage in said rod for connecting the fork thereto, and a guide engaged by said 60 lever and adapted to shift the lever in and out of engagement with said rod and to limit the travel of the lever in either direction.

In testimony whereof I have hereunto set my hand in presence of two subscribing witnesses.

LOUIS MARIE GABRIEL DELAUNAY-BELLEVILLE.
